FOREIGN PATENT DOCUMENTS

686953 5/1964 Canada 181/430

Primary Examiner—Ted Shooman*Assistant Examiner*—Nanda Bondade*Attorney, Agent, or Firm*—Samuels, Gauthier, Stevens & Reppert[57] **CLAIM**

The ornamental design for a headset earcup, as shown and described.

DESCRIPTION

FIG. 1 is a front elevational view of a headset earcup showing our new design, the rear view being a mirror image, the broken line showing of the headset on FIG. 1 is for illustrative purposes only and forms no part of the claimed design;

FIG. 2 is a left side elevational view thereof;

FIG. 3 is a right side elevational view thereof;

FIG. 4 is a top plan view thereof; and,

FIG. 5 is a bottom plan view thereof.
